UNITED STATES PATENT OFFICE.

MICHAEL J. FITZPATRICK, OF PLATTSBURG, NEW YORK.

OIL-BURNER.

1,113,894.

Specification of Letters Patent. Patented Oct. 13, 1914.

Application filed March 22, 1913. Serial No. 756,206.

To all whom it may concern:

Be it known that I, MICHAEL J. FITZPATRICK, a citizen of the United States of America, residing at Plattsburg, in the county of Clinton and State of New York, have invented certain new and useful Improvements in Oil-Burners, of which the following is a specification, reference being had therein to the accompanying drawing.

This invention relates to an oil burner, and the principal object of the invention is to provide a burner which will be very simple in construction, but which will operate very efficiently for converting the liquid fuel into a vapor.

Another object of the invention is to so construct the burner that the various parts may be easily removed, thus permitting the burner to be easily taken to pieces and put together again.

Another object of the invention is to provide the burner with an improved type of nozzle having the interior provided with spiral threads which cause an air or steam jet passing through the nozzle to move with a whirling motion.

With these and other objects in view this invention consists of certain novel combinations, constructions, and arrangements of parts as will be hereinafter fully described and claimed.

In the accompanying drawings:—Figure 1 is a side elevation of the burner. Fig. 2 is a longitudinal sectional view through the burner. Fig. 3 is a top plan view of the burner. Fig. 4 is an end elevation looking into the mouth of the nozzle. Fig. 5 is a perspective view of the nozzle. Fig. 6 is a side elevation of a slightly modified form of burner.

This invention comprises a body portion 10 having its end portions 11 and 12 positioned at substantially right angles to each other and being also provided with a neck 13 positioned in alinement with the end 12. The end portions 11 and 12 as well as the neck 13 are internally threaded to permit various parts to be hereinafter mentioned to be removably connected with the body portion.

The fuel inlet pipe 14 is provided with a threaded section 15 by means of which the inlet pipe may be removably connected with a bushing 16 threaded into the neck 13, and is provided with an enlarged threaded outer end portion 17 by means of which a pipe

leading from the reservoir not shown may be removably connected with the fuel inlet pipe. The inner portion 18 of the fuel inlet pipe is reduced as shown in Fig. 2 and is 60 provided with a tapered end portion 19 in which a small outlet opening 20 is formed. It should be noted that the inner portion 18 and outer portion 17 may be formed integral with the intermediate portion 14 or may be 65 formed from separate pieces of metal piping and threaded into or upon the intermediate section 14.

The tapered nozzle 21 has the walls of its central opening 22 provided with grooves 23 70 similar to the rifling in a rifle barrel, thus causing the air passing through the nozzle to move with a whirling motion. A nipple 24 is carried by the inner end portion of the tapered nozzle and passes through a reducer 75 25 threaded into the threaded neck 12. From an inspection of Fig. 2 it will be readily seen that the pipe 18 does not pass through the center of the nipple 24 and nozzle 21, but passes above the center so 80 that the stream of oil which passes out through the opening 20 will be directed close to the grooves 23, thus causing this stream of oil to be directed into that portion of the air current which has the greatest whirling 85 motion. It should also be noted that by this construction if the oil feeds too freely it will have a greater distance to drop before striking the lower portion of the nozzle and, therefore, the whirling air current will have 90 greater opportunity to break up the stream of oil.

In Fig. 6 there has been shown a slightly modified form of burner in which the nozzle 26 is of greater length than the nozzle 21 95 and is provided with a threaded end portion 27 screwed directly into the threaded neck 12, thus doing away with the need of the nipple 24 and reducer 25. By having the nozzle held in place by a threaded connection the nozzle may be brought nearer to or farther away from the neck 12, and thus the position of the tapered end 19 of the pipe 18 in the nozzle may be regulated. By this arrangement the length of time it takes 100 for the mixed air and oil to pass out of the nozzle may be regulated.

When using this device it is set up as shown in Figs. 2 or 6, and the pipe leading from the oil supply tank is connected with 110 the outer end portion 17 of the pipe 18, thus causing the oil to be fed into this pipe and

pass out through the opening 20 in its inner end. Air or steam is admitted through a suitable pipe leading into the neck 11 from a suitable reservoir and passes through the nozzle 21 where it is caused to have a whirling motion by the grooves 23. This air is under pressure and will, therefore, have a great deal of force which will cause the stream of oil to be broken up into a large number of fine particles. The mixed air and oil passes out through the nozzle into a suitable fire-box and can be ignited.

It is, of course, understood that the pipes which are connected with the threaded end portion 17 and neck 11 will be provided with control valves; thus permitting the flow of air and oil to be regulated.

Having thus described the invention what is claimed as new, is:—

In an oil burner, a casing having a fuel pipe opening, an atomizing fluid inlet at right angles thereto, a tapering nozzle having an adjustable connection with said casing, the bore of said nozzle having spiral grooves thereon, and a fuel pipe extending eccentrically through said casing and nozzle and terminating adjacent said spiral grooves.

In testimony whereof I hereunto affix my signature in presence of two witnesses.

MICHAEL J. FITZPATRICK.
